ATTORNEY

UNITED STATES PATENT OFFICE.

EDWARD COOPER TAYLOR, OF NEW YORK, N. Y.

CLAMP.

Application filed November 25, 1922. Serial No. 603,291.

To all whom it may concern:

Be it known that I, EDWARD C. TAYLOR, a citizen of the United States, residing at New York, in the county of New York and State 5 of New York, have invented certain new and useful Improvements in Clamps, of which the following is a full, clear, and exact description, such as will enable others skilled in the art to which it appertains to make 10 and use the same.

This invention relates to an improvement in clamps and holders, and with respect to its more specific feature to clamps for connecting objects to cylindrical bodies.

15 An object of the invention is to provide a simple, inexpensive mechanism for connecting objects, such as traffic signals, to cylindrical bodies, as for instance radiator collars, in such manner that the pressure of the 20 connecting means on the collar is distributed over a plurality of points.

Another object is to provide a device capable of adjustment to fit different sizes of collars, wherein the adjustment to various 25 sizes is automatic and controlled by the tightening of the clamp on the body.

Another object is to provide a device which will firmly clamp the signal to the collar, without interfering with the normal 30 function of the collar, and without the possibility of injury to the collar.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

In the accompanying drawings forming a part of this specification wherein similar reference characters refer to similar parts throughout the several views,

45 Figure 1 is a side view of a portion of a radiator showing the clamp and holder,

Fig. 2 is a plan view of the clamp, with parts in section,

50 Fig. 3 is an enlarged detail of a portion of the clamp,

Fig. 4, is a front view of the holder detached from the clamp,

55 Fig. 5 is a partial plan view of the blank from which the holder is formed.

The present embodiment of the invention is designed to support traffic signals or li-

cense plates, or both, from the radiator collar of an automobile in such manner that the signal will be supported at the front of the radiator, and the mechanism is so arranged, 60 that it may be applied to collars of varying size, without the necessity for any change in the holder or clamp. The holder comprises a substantially triangular portion consisting of a base 1 and side members 2 converging 65 toward each other from the ends of the base, and at the junction of the members 2 there is an extension 3, the said extension having integral laterally extending rigidifying flanges or wings 4, each of which is provided 70 at its upper edge with a flange 5. The flanges are bent inwardly to overlap, as shown in Fig. 4, and the extension 3 has a longitudinal slot 6, and the base 1 has a pair of aligned slots 7 in its ends, the said slots being 75 designed for a purpose to be presently set forth.

The clamp includes members 8 and 9, designed to be arranged on opposite sides of the radiator cap collar indicated at 10 and 80 the adjacent ends of the members are connected together by telescoping bolts, each composed of an inner member 11, and an outer member 12. Referring to Fig. 2 it will be noticed that the members 8 and 9 are 85 substantially arc shaped, each having angularly disposed engaging faces adapted to engage the collar at circumferentially spaced parts thereof. The members are of a length considerably greater than the diameter of 90 the collar, so that when arranged in the manner shown in Fig. 2, the ends of the members will extend well beyond the collar. The member 9 is provided at each end with a transverse opening having an outwardly disposed spherical seat 13 and an inwardly disposed flaring or funnel-shaped recess 14. The outer member 12 of each telescoping bolt has a head 15 fitting the spherical seat 13 of the opening 13-14, and the head has a transverse kerf or groove 16 for engagement by a screw driver or like tool to turn the section. 100

Each end of the member 8 is longitudinally slotted as shown at 17, to permit the passage of the inner member 11 of the bolt, and that face of the member at each end which is remote from the member 9 has a longitudinal groove 18 registering with the slot, and provided by reaming the outer end of the slot. Each of these grooves 18 is of 110 greatest depth at its inner end, the bottom of the groove gradually inclining toward the

inner end as shown, and the head 19 of the inner member 11 of each bolt is formed on the segment of a sphere, as shown, to fit within the groove 18, the side wall of the 5 groove being shaped to fit the segmental portion of the head. The opening 13-14 and the head 15 provide a ball and socket connection between the bolt and the member 9, and the opening 17-18 and the head 19 provide 10 a sliding connection for the bolt.

The inclination of the bottom of the groove tends to force the head 19 inwardly, when the sections 11 and 12, of the bolt are turned to tighten the members 8 and 9 on 15 the collar. When the clamp is placed on the collar, with the head 19 of the bolt at the outer end of the opening 17-18, and with the bolts extended, it will be obvious that the clamp will slip over a collar of 20 large diameter. When now the bolt sections are turned with respect to each other to tighten the clamp, the inclined grooves 18 will force the heads 19 inwardly, until the bodies of the sections 12 engage the collar 25 at substantially opposite points, where further inward movement of the bolts will be checked. Continued turning of the sections in a direction to tighten the members 8 and 9 will afterwards force the bodies of the 30 bolts more tightly against the collar, and the clamp as a whole will engage the collar at six points, separated from each other at substantially equal distances, and at angular intervals of 60 degrees. Thus the clamp 35 will engage the collar at separated points throughout the circumference thereof, and the pressure will be widely distributed, and at points such that there will be no tendency of any portion of the collar to spring outward under any pressure. The stress is substantially all radial to the collar, that is in 40 a direction which it is best adapted to resist. Preferably the heads 19 beyond the segmental portion are polygonal in cross-section to facilitate the turning thereof. The head 19 may be held by a wrench, and the head 15 turned by a screw driver or the screw driver may be used to hold the section 45 12, while the section 9 is turned by the wrench.

The member 8 of the clamp has an extension 20 which is adapted to lap upon the flanges 5 of the holder, and the said extension and the flanges have registering openings as shown, for receiving rivets 21, to secure the extension to the flanges of the holder. At the end remote from the clamp 55 the extension has a substantially wedge shaped depending flange 22, which is adapted to engage the upper edge of the back plate 23 of the traffic signal indicated at 24, and clamp the said plate 23 between the flange and the front of the extension 3. The extension also has lateral wings 25 at its opposite sides and at its front end, which exten-

sions are longitudinally slotted as shown. The plate 23 is connected to the base 1 of the holder, by means of bolts 26 which are passed through openings in the base of the plate and the openings 7 before mentioned, 70 and are engaged by nuts behind the holder. The license plate indicated at 27 may be supported below the traffic signal, by means of the bolts 26, and in this position it is illuminated by the traffic signal, the said 75 signal having a lamp for this purpose.

When it is not desired to use the traffic signal, it may be detached, by removing the bolts 26. The license plate may then be connected with the wings 25 and the base 1 of the holder, the upper edge of the plate being connected with the wings, and the lower end of the holder base. The holder is stamped or cut from sheet metal or other suitable material, and the members 8 and 9 80 may be cast or otherwise formed. The improved clamp automatically adapts itself to any size radiator collar, within limits. When extended to its largest diameter, it 85 will fit over collars of the largest size. 90 When in place, the mere tightening of the sections 11 and 12 of the bolts will cause the device to adjust itself to the collar, and to engage the collar at the six points of contact. 95

As many changes could be made in the above construction and many apparently widely different embodiments of this invention could be made without departing from the scope thereof, it is intended that all 100 matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween. 110

Having described my invention, what I claim as new and desire to secure by Letters Patent is:—

1. In a device of the class described, in combination, opposing clamping members adapted to engage a supporting body, a securing member for forcing said clamping members into clamping position upon said body, and a connection between said clamping members and said securing member including an elongated seat to automatically urge said securing member into clamping contact with said supporting body when said securing member is tightened to force said clamping members into clamping position. 115 120 125

2. In a device of the class described, in combination, opposing clamping members adapted to engage a supporting body, a securing member for forcing said clamping 130

- members into clamping position upon said body, one of said clamping members having an opening with a spherical seat and a flaring recess for the reception of said 5 securing member, and the other clamping member having a seat cooperating for automatically urging the securing member toward and into clamping contact with said supporting body when said securing 10 member is tightened to force said clamping members into clamping position.
3. In a device of the class described, in combination, opposing members, means to connect the adjacent ends of the members, 15 and a connection between the said means and the members for constraining the said means to move inwardly as the members are drawn together, including cooperating cam surfaces on one of the members and the connecting means.
4. In a device of the class described, in combination, opposing members, and contractible bolts connecting adjacent ends of the members, and having pivotal connection 25 with one of said members and lateral sliding connection with another of said members.
5. In a device of the class described, in combination, opposing members, contractible 30 bolts connecting adjacent ends of the members, and cooperating cam surfaces in connection with the members and the bolts for constraining the bolts to move inwardly as they are tightened.
- 35 6. In a device of the class described, in combination, opposing members, contractible bolts connecting adjacent ends of the members, and cooperating cam surfaces between one of said members and the bolts for constraining the bolts to move inwardly at the 40 ends adjacent to the said member when they are tightened.
7. In a device of the class described, in combination, opposing clamping members 45 adapted to engage a body, securing means for forcing said clamping members into position to clamp said body, said securing means also effecting independent clamping action against said body.
- 50 8. In a device of the class described, in combination, opposing members, contractible bolts connecting adjacent ends of the members, a universal joint connection between the bolts and one of the members, and a slotted connection between the bolts and the other member for permitting the adjacent ends of the bolts to move longitudinally of the member.
- 55 9. In a device of the class described, in combination, opposing members, contractible bolts connecting adjacent ends of the members, a universal joint connection between the bolts and one of the members, a slotted connection between the bolts and the other member for permitting the adjacent ends 60 of the bolts to move longitudinally of the member, and cooperating cam surfaces for constraining the said ends of the bolts to move inwardly when they are tightened.
10. In a device of the class described, in combination, opposing substantially arc shaped members adapted to engage opposite sides of a cylindrical body and contractible bolts connecting the ends of the members, 65 said bolts having a ball and socket connection with one member, and a sliding connection with the other member radial to the cylindrical body.
11. In a device of the class described, in combination, opposing substantially arc shaped members adapted to engage opposite sides of a cylindrical body and contractible bolts connecting the ends of the members, 70 said bolts having a ball and socket connection with one member, and a sliding connection with the other member radial to the cylindrical body, and cooperating cam surfaces in connection with the said last named member and the bolts for constraining the bolts to move inwardly as they are tightened.
12. In a device of the class described, in combination, opposing arc shaped members having their inner edges shaped to engage a cylindrical body at points spaced apart from each other, means engaging the adjacent 75 ends of the members for drawing them together, said means including contractible bolts having a universal joint connection with one member and a slotted connection with the other member for permitting the adjacent ends of the bolts to move longitudinally of said member.
13. In a device of the class described, in combination, opposing arc shaped members having their inner edges shaped to engage a cylindrical body at points spaced apart from each other, means engaging the adjacent ends of the members for drawing them together, said means including contractible bolts having a universal joint connection 80 with one member and a slotted connection with the other member for permitting the adjacent ends of the bolts to move longitudinally of said member, and means for constraining the adjacent ends of the bolts to move inwardly when they are tightened.
14. In a device of the class described, in combination, a signal support including a substantially triangular member for carrying the signal and having at one apex a supporting extension provided with rigidifying flanges, and a laterally disposed supporting arm merging with said flanges.
15. In a device of the class described, in combination, a signal support including a substantially triangular member for carrying the signal and having at one apex a supporting extension provided with rigidifying flanges, a laterally disposed supporting arm merging with said flanges, and a clamp for 85 90 95 100 105 110 115 120 125 130

supporting the signal support and having a lug lapping said supporting arm.

16. In a device of the class described, in combination, a signal supporting bracket having a supporting plate provided with rigidifying flanges having lapping extensions providing a rigidifying laterally disposed supporting arm, and a clamp including a pair of clamping members, one of which has a supporting lug lapping said supporting arm and secured thereto.

17. In a device of the class described, in combination, a holder for a traffic signal comprising a substantially triangular member to which the signal is connected and having a lateral arm at its top, a clamp for connecting said member with a radiator collar, said clamp having a plurality of clamping members, one of which has an integral lug lapping upon said arm and secured thereto, said lug having a depending flange engaging the outside of the holder and bevelled on its inner face.

18. In a device of the class described, in combination, a pair of substantially arc shaped members adapted to engage opposite sides of a radiator collar, and shaped to contact with the collar at points spaced apart from each other, sectional bolts engaging the ends of the members for drawing them together, the sections having threaded engagement, the bolts having ball and socket connections with one member and sliding connections with the other, and cooperating

cam surfaces in connection with the said member and the bolts for moving said bolts inwardly when they are tightened.

19. In a device of the class described, in combination, a traffic signal and license plate holder comprising a plate having an extension at its top provided with integral lateral wings of greater height than the extension, the wings being bent to lie substantially parallel and the tops thereof being bent to overlap.

20. In a device of the class described, in combination, a traffic signal and license plate holder comprising a plate having an extension at its top provided with integral lateral wings of greater height than the extension, the wings being bent to lie substantially parallel and the tops thereof being bent to overlap, and a clamp for engaging the inlet collar of a radiator connected to the flanges.

21. In a device of the class described, in combination, a traffic signal and license plate holder comprising a plate having an extension at its top provided with integral lateral wings of greater height than the extension, the wings being bent to lie substantially parallel and the tops thereof being bent to overlap, a clamp for engaging the inlet collar of a radiator and having a lug lying upon the flanges and secured thereto.

In testimony whereof I affix my signature.

EDWARD COOPER TAYLOR.
